UNITED STATES PATENT OFFICE.

ANDERS ANDERSEN PINDSTOFTE, OF COPENHAGEN, DENMARK.

BOTTLING APPARATUS.

No. 885,785.

Specification of Letters Patent.

Patented April 28, 1908.

Application filed October 4, 1906. Serial No. 337,539.

To all whom it may concern:

Be it known that I, ANDERS ANDERSEN PINDSTOFTE, manufacturer, subject of Denmark, residing at Frederiksberg Allé No. 62, 5 Copenhagen, in the Kingdom of Denmark, have invented new and useful Improvements in Bottling Apparatus, of which the following is a specification.

The invention has for its object improvements in bottling apparatus in which during the filling of the bottles they are pressed against an elastic mouthpiece on the filling pipe, the especial object being to support the bottle table in such a manner that when the 10 bottles are being changed the table is readily and speedily movable upwards and downwards under the influence of an approximately equal counterweight, while on the other hand when the bottle is being filled it 15 is firmly held against the mouthpiece on the filling pipe under the influence of a larger counterweight.

A constructional form of the invention is illustrated in the accompanying drawing 20 which represents a vertical section through a bottling apparatus, some parts being in elevation.

On the frame *a* the supply pipe *b* for the liquid is supported. One or more cocks *c* 25 with filling pipes *d* are arranged on the supply pipe *b* and during filling the bottles are pressed against their elastic mouthpieces *e*. Each bottle is carried by a table *f* the guide rod *g* of which passes through guiding parts 30 in the frame *a* and is provided with an intermediate piece *h* in two parts. In this part *h* there is movably mounted a pulley *i* around which a chain or cord *k* runs so that the bottle table is carried by this chain. One 35 end of the chain is fixed in a projection *l* on the frame *a*, while the other end is carried over a roller *m* mounted in the frame to a counterweight *n* which is carried by the chain, its weight approximately corresponding 40 to that of the table when carrying an empty bottle, the counterweight *n* which is provided with a number of teeth *o* suspended in a heavy or spring loaded hollow weight *p* carrying a two-armed locking pawl *r*, the arm 45 *s* of which normally engages one of the teeth *o* through a slot *q* in the hollow weight *p*, so that the counterweight *n* carries the weight *p*. Consequently the two weights are 50 coupled together and form normally a single 55 heavy counterweight.

By means of suitable mechanism mounted

in the frame, for example by means of a treadle *v* mounted in the lower part of the frame *a* the heavy weight *p* may be lifted. When the weight *p* is lifted the upper arm *t* 60 of the pawl *r* engages a projection *u* on the frame *a*, thereby bringing the pawl arm *s* out of engagement with the teeth of the counterweight *n*, so that the connection between the weights *n* and *p* is broken, and the bottle 65 table is counterbalanced by the weight *n*.

When the treadle *v* is released the weight *p* returns to its normal position and the arm *s* of the pawl *r* reengages with the teeth *o*. Consequently the two weights are again 70 coupled together and the bottle table is again counterbalanced by the combined weights *n* and *p*.

The operation is as follows: When a bottle is to be applied to a filling pipe *d*, the weight 75 *p* is lifted by means of the treadle *V* thereby bringing the pawl member *s* out of engagement with the counterweight *n*. Then, still pressing on the treadle *v*, the bottle table may be moved downwards without exerting any 80 force and the empty bottle placed upon it. Now if it is desired to again raise the table until the mouth of the bottle resting upon it bears against the elastic mouthpiece *e*, the treadle *v* is released, thereby allowing the 85 weight *p* to descend somewhat. At the same time the pawl member *s* of the pawl *r* will move through the slot *q* and engage in one of the teeth *o* thereby connecting the weight *p* with the weight *n* and pressing the bottle to 90 be filled against the mouthpiece *e*. Consequently the changing of the bottles presents no difficulty, does not necessitate any strenuous effort and proceeds speedily and uniformly. In addition to this the arrangement described presents the further advantage that the application of the bottle to the mouthpiece is effected by the raised counterweight readily, without friction and invariably uniformly, whether the bottle is large or 95 small, and the chain may be lengthened or shortened by varying its attachment to the projection *l*.

Having now particularly described and ascertained the nature of my said invention 105 and in what manner the same is to be performed, I declare that what I claim is:

1. In an apparatus of the character described, the combination of a supporting frame-work, a feed-pipe mounted thereon 110 and provided with a suitable outlet, a vertically-movable bottle-carrying table mount-

ed beneath said outlet, a weight mounted in the frame-work of said apparatus, means for raising said weight, a counter-weight mounted within said weight and provided with a plurality of teeth, a pawl mounted on the first-named weight and adapted to engage said teeth, a pulley mounted on said bottle-carrying table, a second pulley mounted on said frame-work, and a chain connected to 10 said frame-work and to said counter-weight and riding over said pulleys.

2. In an apparatus of the character described, the combination of a supporting frame-work, a feed-pipe mounted thereon and provided with a suitable outlet, a bottle-carrying table movably mounted beneath said outlet, a weight movably mounted in said frame-work, a plurality of pulleys mounted on said table and on said frame-work, a chain secured to said frame-work and riding over said pulleys, means for raising said weight, a counter-weight mounted within said weight and connected to said chain and provided with a plurality of teeth and a pawl member secured to the first-named weight and adapted to lock said counter-weight to said weight, for the purpose described.

3. In an apparatus of the character described, the combination of a suitable frame-work, a feed-pipe mounted thereon and provided with an outlet having an elastic mouth-piece, a bottle-carrying table movably mounted beneath said outlet, a weight slidably mounted in said frame-work, means for

raising said weight, a plurality of pulleys mounted on said table and on said frame-work, a counter-weight mounted within the first-named weight and provided with teeth on one side thereof, a chain secured to said frame-work and riding over said pulleys and having its other end secured to said counter-weight, and a pawl member secured to the first-named weight and adapted to engage the teeth of said counter-weight.

4. In an apparatus of the character described, the combination of a frame-work, a feed-pipe mounted thereon and provided with a suitable outlet having an elastic mouth-piece, a vertically movable bottle-carrying table mounted beneath said mouth-piece, a weight suitably mounted in said frame-work, means for raising said weight, a counter-weight located within said weight, a plurality of pulleys mounted on said table and on said frame-work, a chain connected to said frame-work and riding over said pulleys and secured at its other end to said counter-weight, a rack formed on one side of said counter-weight, and a pawl member pivotally mounted on the first-named weight and adapted to engage the rack of said counter-weight.

In testimony whereof I have signed my name to this specification in the presence of 65 two subscribing witnesses.

ANDERS ANDERSEN PINDSTOFTE.
